Plamire & Bain
Attorney

UNITED STATES PATENT OFFICE.

JAMES LAWRENCE LAW, OF PUNXSUTAWNEY, PENNSYLVANIA.

RECEPTACLE FOR EXPLOSIVES.

Application filed March 6, 1925. Serial No. 13,542.

To all whom it may concern:

Be it known that I, JAMES L. LAW, a citizen of the United States, residing at Punxsutawney, in the county of Jefferson and State of Pennsylvania, have invented certain new and useful Improvements in a Receptacle for Explosives, of which the following is a specification.

This invention relates to improvements in receptacles which are principally adapted to be used for carrying explosives used in mining operations.

One of the important objects of the present invention is to provide a receptacle of the above mentioned character, wherein means is provided for receiving and supporting dynamite caps or detonators which are used in various mining operations, means being provided for spacing said explosives 20 from each other in the receptacle.

A further object of the invention is to provide a receptacle of the above mentioned character which includes a means for receiving dynamite caps, additional means being provided for accommodating the lead in wires associated with the caps.

A still further object of the invention is to provide a receptacle of the above mentioned character wherein a slidable cover is associated therewith, means being associated with the receptacle and the cover for locking the latter in a closed position to prevent the accidental displacement of the explosives from the receptacle.

A still further object is to provide a receptacle of the above mentioned character which is simple in construction, inexpensive, and furthermore adapted to the purpose for which the same is designated.

Other objects and advantages of this invention will become apparent during the course of the following description.

In the accompanying drawing forming part of this specification, and in which like numerals are employed to designate like parts throughout the same:—

Figure 1 is a top plan view of the receptacle embodying my invention with the slidable cover in an open position.

Fig. 2 is a sectional view through the receptacle and the cover, the latter being shown in a closed position, and

Fig. 3 is a detail perspective view of the block.

In the drawing wherein for the purpose of illustration is shown the preferred embodiment of my invention, the numeral 1 designates a receptacle which is formed of any suitable non-conductive material, preferably wood and is open at its top. The top of the receptacle is provided with a substantially dovetailed groove 2 for receiving the slid- 60 able cover 3.

The outer end portion of the slidable cover 3 is provided with an opening 4, the top portion of the cover around the opening being cut away as illustrated at 5 to provide a finger hold whereby the cover may be opened. For the purpose of holding the cover in a locked position over the open upper end of the receptacle, there is provided in the outer side of the receptacle a spring latch. The latter includes a pin 6 which is adapted for vertical sliding movement in a suitable opening 7 provided therefor in the side of the receptacle adjacent the open top thereof.

The slidable pin 6 is provided with a longitudinal slot 8 into which extends the transverse pin in a manner clearly illustrated in Fig. 2. This construction provides a means for limiting a slidable movement of the pin. Any suitable resilient means such as is illustrated at 10 is disposed in the bottom of the opening or recess 7 and engages the bottom of the pin 6 and normally urges the same upwardly so that the upper end of the pin will extend through the opening 4 provided in the cover 3. By depressing the pin 6 against the tension of the resilient member 10, the upper end of the pin may be brought out of engagement with the opening 4 so as to facilitate the sliding movement of the cover in order to uncover the receptacle.

Cooperating with the upper end of the upwardly urged pin 6 is a longitudinally extending groove 11 provided in the bottom face of the cover. This construction provides a means whereby the outward sliding movement of the cover with respect to the receptacle is limited, it being understood of course that the longitudinally extending groove 11 communicates at one end with the opening 4, while its other end terminates at a point adjacent the inner end of the cover in the manner as clearly illustrated in Fig. 2.

The holder for the explosive caps or dynamite comprises a substantially rectangular shaped block 12, the latter being adapted to be removably inserted within the receptacle

1. The block 12 which is also formed of the same material as the receptacle 1 is of substantially the same width as the width of the interior of the receptacle as is clearly illustrated in Figs. 1 and 2. The block 12 is preferably of such thickness as to be disposed intermediate the sides of the receptacle and for further holding the block in the central portion of the receptacle, 10 there is provided on each of the sides of the block, the laterally extending rib 13. The ribs are arranged in parallel spaced relation with respect to each other and extend for substantially the full length of the block. 15 The outer edges of these ribs cooperate with the respective sides of the receptacle so that a plurality of compartments such as are shown at 14 will be formed in the receptacle, the purpose of which will be hereinafter 20 more fully described.

The block 12 is further provided with a plurality of vertically extending cylindrical cells or chambers 15, the same being arranged in parallel spaced relation with respect to each other and extending from the top of the block to a point adjacent the bottom of the same. Any number of these cells or chambers may be provided as is desired and the same provides a means for receiving the explosive caps or dynamite which is used for various mining operations in the manner well known in the art.

The upper edge of the block 12 is further provided with a series of transversely extending notches 16 each of which cooperates with the upper portion of the respective cells or chambers as is clearly illustrated in the drawing.

When the block 12 is inserted within the receptacle 1, and is arranged in the manner shown in Fig. 1 of the drawing, the explosive caps or detonators may be readily inserted in the several cells or chambers 15. The lead in wires which are associated with 45 the explosive caps which are of great length are folded. The wires will then be received within the respective chambers 14 provided therefor, it being understood that the notches 16 will accommodate the portions of

the wires which are connected with the explosives. When the cover 3 is in a closed position, there will be no possibility of the explosives falling out of their respective cells or chambers and furthermore damage to the explosives will be prevented.

It will thus be seen from the foregoing description, that a receptacle for carrying explosives used in mining operations has been provided which is very simple in construction, the parts being so arranged as to assure the safe handling of the explosives.

By further constructing the receptacle and the component parts thereof of non-conductive material, there will be no possibility of the explosives contained therein becoming accidentally ignited.

While I have shown the preferred embodiment of my invention, it is to be understood that various changes in the size, shape and arrangement of parts may be resorted to without departing from the spirit or scope of the appended claim.

Having thus described my invention, what I claim as new is:

A device of the class described comprising an open top receptacle, a cover therefor adapted for slidable movement with respect to the receptacle, said cover having an opening formed in one end thereof, and provided with a longitudinally extending groove in the bottom, one end of the groove communicating with said opening, a block having a series of explosive receiving cells formed therein removably supported within the receptacle, and means for locking the cover in a closed position comprising a spring actuated latch arranged in one of the sides of the receptacle adjacent the upper edge thereof, said latch cooperating with the opening formed in the cover, said latch being adapted for cooperation with the opposite end of the groove formed in the bottom of the cover for limiting the outward movement thereof.

In testimony whereof I affix my signature.

JAMES LAWRENCE LAW.
